(57) **CLAIM**

The ornamental design for a vehicle suspension spacer, as shown and described.

DESCRIPTION

FIG. 1 is a top front perspective view of a vehicle suspension spacer;

FIG. 2 is a bottom front perspective view thereof;

FIG. 3 is a front elevation view thereof, the left side elevation view, the right side elevation view and the rear elevation view being identical images thereof;

FIG. 4 is a top elevation view thereof; and,

FIG. 5 is a bottom elevation view thereof.

The broken lines shown in the drawings depict portions of the vehicle suspension spacer that forms no part of the claimed invention.
